CLAIM

The ornamental design for a music board, as shown and described.

DESCRIPTION

FIG. 1 is a top front perspective view of a music board showing the new design;

FIG. 2 is a front elevation view thereof;

FIG. 3 is a rear elevation view thereof;

FIG. 4 is a left side view thereof;

FIG. 5 is a right side view thereof;

FIG. 6 is a top view thereof; and,

FIG. 7 is a bottom view thereof.

The broken lines showing portions of the music board are included for the purpose of illustrating portions of the article and form no part of the claimed design.

1 Claim, 5 Drawing Sheets
